LIGHT FLARE

Leonard D. Jackson, Alexandria, Va.

Application December 9, 1944, Serial No. 567,505

12. Claims. (Cl. 9—8.3)

(Granted under Title 35, U. S. Code (1952),
sec. 266)

1

The present invention relates to a light flare of the type suitable for use during night operations for silhouetting enemy targets such for example as battleships, airplane carriers, transports or any other surface craft.

The principal object of the invention is the provision of a new and improved light flare adapted to be launched from a motor torpedo boat or similar surface craft and which will float upon the surface of a body of water and give sufficient light to enable observers or gunners to see and fire upon enemy ships or other targets before the launching craft is detected by the enemy.

Another object of the invention is the provision of a new and improved light flare adapted to float upon the surface of a body of water and having a time delay unit arranged therein whereby sufficient time will elapse before ignition of the pyrotechnic flare material to allow the torpedo boat to be well out of range of enemy gun fire before the flare material is ignited.

Another object is to provide a new and improved light flare adapted to be used as an emergency night landing flare for aircraft and, if so desired, may also be used for illuminating an area sufficiently to enable rescue workers to see to perform their duties after a plane crash or shipwreck at sea.

A further object of the invention is the provision of a light flare having new and improved means for preventing moisture from contacting the time delay unit during transportation and storage of the flare in which sparks created by a flashback during burning of the time delay fuse are prevented from contacting the pyrotechnic material and causing premature firing thereof.

A still further object is to provide a new and improved light flare which is economical to manufacture, reliable in operation and which possesses the qualities of durability during handling and transportation.

Still other objects, novel features, and advantages of the invention will become apparent from the following description, taken in connection with the accompanying drawings, wherein:

Fig. 1 is a view partly in elevation and partly in section of a float flare constructed in accordance with a preferred embodiment of the present invention;

Fig. 2 is an enlarged top plan view of the float light of Fig. 1;

Fig. 3 is an enlarged sectional view taken on the line 3—3 of Fig. 1; and,

Fig. 4 is an enlarged fragmentary sectional

view of the upper portion of the float light showing the firing mechanism including the time delay unit and associate parts thereof.

Referring to the drawings wherein similar reference characters are employed to designate like parts throughout the several views, the float flare shown thereon is generally indicated by the numeral 10, and comprises an elongated cylindrical buoyant body 11 composed of wood or of any other material suitable for the purpose and adapted to be launched from a motor torpedo boat or aircraft in flight, as the case may be. The body 11 is provided with a centrally disposed cylindrical chamber or bore 12, extending therethrough and arranged within the bore is a pyrotechnic unit generally indicated by the reference character 13. The pyrotechnic unit comprises a plurality of tubes or containers 14, 15 and 16, each of which is provided with a quantity of pyrotechnic material therein as indicated by the reference character 17 and consisting of ingredients well known in the art and uniformly mixed thereby to insure positive ignition and uniform burning thereof. The intermediate container 15 is provided with threaded end portions 18 and 19 respectively adapted to have threaded engagement with the threaded portions 21 and 22 of the containers 14 and 16 whereby the containers may be readily assembled to provide a continuous pyrotechnic candle, it being understood, however, that the pyrotechnic material is pressed into each of the containers before assembly thereof. Discs 23 and 24 composed of felt, silk or of any other material suitable for the purpose, are disposed between the pyrotechnic charges within the containers 14, 15 and 16 respectively thereby preventing frictional contact of the charges as the containers are screwed together during assembly thereof, whereby premature firing of the pyrotechnic charges are prevented.

Before inserting the pyrotechnic unit 13 into the chamber or bore 12, a copious amount of cement is applied thereto of any suitable type, preferably the type known in the trade as Pettman cement. It is understood however, that if so desired, a coating of cement may also be applied to the wall of the bore 12. Therefore, it will be apparent that the pyrotechnic unit is securely sealed within the bore 12 by the cement 25 in such a manner as to prevent moisture from contacting the pyrotechnic charges within the pyrotechnic containers. A metallic nose cap 26, containing a weight 27 is secured to the lower end of the body 10 in any suitable manner, prefer-

ably by nails or the like, indicated by the reference character 23. A fuse and pressure housing composed of any material suitable for the purpose and generally indicated by the reference character 29, and comprising an annular portion 31 which includes a conical portion 32 is adapted to extend above the body 11. The annular portion 31 of the fuse housing is secured within a recess 33 provided in the upper end of the body 11 in any suitable manner, preferably as by 10 wood screws or the like, indicated by the reference character 34. A coating of Pettman cement 35 is applied to the annular portion 31 of the fuse housing and also to the wall of the recess 33 thereby providing a moistureproof joint therebetween.

The upper end of the housing is provided with an opening 36 adapted to be closed by a transparent disc 37 held in position by a retaining ring 38. Screws 39 are adapted to pass through registering openings in the retaining ring and transparent disc and are adapted to have threaded engagement with the threaded openings 41 provided in a flange 42 carried by the housing 29 thereby clamping the disc 37 between the flange and the retaining ring 38. The retaining ring 38 includes a flange 43 adapted to engage a portion of the housing 29 to which a coating of cement 44 of the type heretofore described has been applied. The housing 29 is thus hermetically sealed, thereby not only excluding moisture therefrom but also providing a heat and pressure chamber therein. A firing unit generally indicated by the reference character 45 which is similar to the conventional firing unit employed with hand grenades is mounted in the transparent disc 37 and includes a body portion 46, a pivotally mounted striker 47 arranged within the body, a firing spring 48, a lever 49 for holding the striker in cocked position, a safety pin 50 for retaining the lever in place on the firing unit and the usual primer 51 mounted within the body 46.

The firing unit 45 is secured to the transparent disc 37 in any suitable manner, preferably by a lock nut 52 adapted to have threaded engagement with a threaded nipple 53 integrally connected to the body portion 46 of the firing unit. The nipple 53 extends through an opening 54 provided in the disc 37 and into the fuse housing 29. A gasket 55 is disposed between the disc 37 and the body portion 46 and, as the lock nut 52 is tightened upon the threaded nipple 53, the nut will engage the disc 37 thereby compressing the gasket between the housing 29 and the disc and providing a moistureproof joint therebetween. A reduced tubular member 56 is integrally connected to the nipple 53 and a brass tube 57 is pressed into a bore 58 provided therein, thereby forming a support for the tube within the fuse housing 29. The brass tube 57 extends below the end of the tubular member 56 and is adapted to receive and support a portion of a time delay or slow burning fuse 59 therein. One end of the time delay fuse 59 is held within the tube 57 in predetermined spaced relation with respect to the primer 51 in any suitable manner as by crimping the tube at two or more points along the length thereof as indicated by the reference character 61. A length of quickmatch 62 is embedded in the end of the fuse 59 subjacent the primer thereby providing means for igniting the time fuse after the lever 49 has been released by the operator.

The other end of the time delay fuse extends

into a sack or pouch 63 which contains a quantity of starter mixture of any well known type, the sack being composed of any material suitable for the purpose such, for example, as silk 5 and is held in position upon the fuse by a length of cotton cord 64 twined about the sack 63 and having the free ends thereof securely tied together. There is also provided a combustible moistureproof container or capsule generally indicated by the reference character 66 composed of any material suitable for the purpose and comprising a cylindrical member 67 having an opening 68 provided therein for the passage of one end of the time delay fuse 59 therethrough so that the sack 63 may be secured thereto and arranged within the combustible moistureproof container 66. Caps 69 and 71 seal the ends of the cylindrical member 67, thereby hermetically sealing the sack 63 within the combustible moistureproof container 66. The intermediate portion of the time delay fuse 59 is coiled as indicated by the reference character 72, the outer convolution of each coil thereof frictionally engages the inner surface of the housing 29 thereby holding the fuse and the combustible container 66 in a relative fixed position within the housing 29, the fuse being additionally cemented to the cylindrical member 67 as at 70. The combustible housing 66 is adapted to rest on a first fire composition 73 arranged upon the pyrotechnic candle, thereby providing means for igniting the pyrotechnic candle after the operator has released the lever 49. The spring tensioned striker 47 is thus allowed to impinge the primer 51 with sufficient force to cause firing thereof which produces a burst of flame therefrom. The flame ignites the quick match embedded in the end of the time fuse 59 thereby causing ignition of the time fuse and allowing a predetermined period of time to elapse before the starter mixture is ignited thereby. Upon ignition of the starter mixture sufficient heat and fire are produced to cause disintegration of the sack 63 and the combustible container 66 thereby allowing hot slag produced by the burning of the starter mixture to come into contact with the first fire composition 73 to cause ignition thereof and, in turn, igniting the pyrotechnic candle contained within the pyrotechnic unit 13.

50 A silk tubing 74 encloses the time delay fuse 59 whereby sparks caused by a flashback, which sometimes occurs during burning of the fuse, are prevented from coming into contact with the pyrotechnic candle and causing premature firing 55 of the pyrotechnic material. One end of the silk tubing 74 is adapted to be slipped over the tubular member 56 and is held thereon in any suitable manner, preferably by a length of cord twined thereabout, as indicated by the reference 60 character 75, the free ends thereof being securely tied together. The transparent disc 37 is provided with a plurality of openings 76 adapted to be sealed by a sealing compound 77 suitable for the purpose such, for example, as beeswax or any other like substance, thereby preventing moisture from seeping therethrough and causing deterioration of the pyrotechnic materials during transportation and storage. It is understood, however, that the sealing compound 77 is quite strong at ordinary temperatures but softens when subjected to heat.

65 As the time delay fuse burns, heat and gas will be produced therefrom and when a sufficient amount of heat is generated within the housing 70 29, the sealing compound will melt, thereby un-

sealing the openings 16 and allowing a predetermined amount of gas to escape therethrough; thereby relieving the pressure within the housing 29. The transparent disc 31 is provided with a circumferential weakened portion 73 and as the gases accumulate within the housing 29 caused by the ignition of the charges of the fuse 59 and/or the first fire composition 73, the weakened portion of the disc will give way when excess pressure has been exerted thereon due to the expansion of the gases within the housing 29, whereby that portion of the disc enclosed by the weakened portion of the disc and the firing unit carried thereby will be forcibly removed from the disc 31, thus providing an unobstructed passage for the flame caused by the burning pyrotechnic candle.

While the light flare is particularly adapted for launching from a motor torpedo boat, it is to be understood that, if so desired, the flare can be launched from an aircraft in flight by employing a parachute attached thereto to prevent the fire from striking the water with sufficient force to cause damage thereto.

It will be understood that the foregoing description and accompanying drawings comprehend only the general embodiment of the invention and that various changes in construction, proportion and arrangement of the parts may be made within the scope of the appended claims without sacrificing any of the advantages of the invention.

The invention herein described and claimed may be manufactured and used by or for the Government of the United States of America for governmental purposes without payment of any royalties thereon or therefor.

What is claimed as new and desired to be secured by Letters Patent of the United States is:

1. A light emitting device adapted to float upon the surface of a body of water and comprising an elongated buoyant body having a bore extending therethrough, a pyrotechnic candle arranged within said bore, a housing secured to said buoyant body, a closure for sealing said housing hermetically to form a heat and pressure chamber, firing means supported by said closure, said firing means including means for igniting said pyrotechnic candle, means for firing said firing means, a plurality of sealed pressure relief means in said closure and in communication with the heat and pressure chamber, said pressure relief means being adapted to be unsealed by the heat and pressure generated by said candle igniting means, and means in said closure and adapted to be ruptured by the pressure generated by the ignition of said pyrotechnic candle whereby a portion of the closure and the firing means supported thereby are forcibly removed from said housing.

2. A light emitting device adapted to float upon the surface of a body of water and comprising an elongated buoyant body having a bore extending therethrough, a pyrotechnic candle arranged within said bore, a housing secured to said buoyant body, a disc for sealing said housing hermetically to form a heat and pressure chamber therein, a firing unit supported by said disc, said firing unit including means for igniting said pyrotechnic candle to produce a flame therefrom, means for firing said firing unit, a plurality of sealed pressure relief means in said disc in communication with the heat and pressure chamber, said pressure relief means being adapted to be unsealed by the heat and pressure generated by said candle igniting means, and means in said closure and adapted to be ruptured by the pressure generated

by the ignition of said pyrotechnic candle whereby a portion of the disc and the firing means supported thereby are forcibly removed from said housing to render the device effective to emit light therefrom.

3. A light emitting device adapted to float upon the surface of a body of water and comprising an elongated buoyant body having a bore extending therethrough, a pyrotechnic candle arranged within said bore, a housing secured to said buoyant body, a disc for sealing said housing hermetically to form a heat and pressure chamber therein, a firing unit supported by said disc, means for firing the firing unit, a time delay fuse arranged within said housing and adapted to be fired by said firing unit, said time delay fuse having means for igniting said pyrotechnic candle in predetermined time delayed relation with respect to the firing of the firing unit, flexible means enclosing said time delay fuse whereby a flashback of said fuse during the burning thereof is prevented from prematurely firing said pyrotechnic candle, a plurality of sealed pressure relief means provided in said disc in communication with said heat and pressure chamber, said pressure relief means being adapted to be unsealed by the heat and pressure generated by said time delay fuse, and means in said disc and adapted to be ruptured by the pressure generated by the ignition of said pyrotechnic candle whereby a portion of the disc and the firing means supported thereby are forcibly removed from said housing.

4. A light emitting device adapted to be launched from a surface craft and comprising an elongated buoyant member having a bore extending therethrough, means secured to said buoyant member for causing the device to float upon the surface of a body of water in an upright position, a pyrotechnic candle arranged within said bore and including a first fire composition, a housing secured to said buoyant member at the upper portion thereof, a disc for sealing said housing hermetically to form a heat and pressure chamber therein, a firing unit supported by said disc, means for firing said firing unit, a time delay unit arranged within said housing and adapted to be fired by said firing unit, said time delay unit having means for igniting said first fire composition in predetermined time delayed relation with respect to the firing of said firing unit, a plurality of sealed pressure relief means in said disc in communication with the heat and pressure chamber, said pressure relief means being adapted to be unsealed by the heat and pressure generated by said time delay unit, and means in said disc and adapted to be ruptured by the pressure generated by the ignition of said pyrotechnic candle whereby a portion of the disc and the firing means supported thereby are forcibly removed from said housing.

5. A light emitting device adapted to float upon the surface of a body of water and comprising an elongated buoyant body having a bore extending therethrough, a pyrotechnic candle including a first fire composition arranged within said bore, a housing secured to said buoyant body, a disc for sealing said housing hermetically to form a heat and pressure chamber therein, a firing unit supported by said disc and having one end of a time delay fuse arranged therein, a pouch enclosing the other end of said fuse and secured thereto, said pouch containing a quantity of starter mixture therein, a combustible moistureproof container enclosing said pouch, means enclosing said time delay fuse for preventing

premature firing of said pyrotechnic candle as the time delay fuse burns, said container being adapted to rest upon said first fire composition, a plurality of sealed pressure relief means in said disc in communication with said heat and pressure chamber, said pressure relief means being adapted to be unsealed by the heat and pressure generated by said time delay fuse during burning thereof, and means in said disc and adapted to be ruptured by the pressure generated by the ignition of said pyrotechnic candle whereby a portion of the disc and the firing unit supported thereby are forcibly removed from said housing to render the device effective to emit light therefrom.

6. A light emitting device adapted to float upon the surface of a body of water and comprising an elongated buoyant body having a bore extending therethrough, a pyrotechnic candle arranged within said bore, a housing secured to said buoyant body, a closure for sealing said housing hermetically to form a heat and pressure chamber therein, firing means supported by said closure, a time delay fuse adapted to be ignited by said firing means, said time delay fuse including means for igniting said pyrotechnic candle, means enclosing said time delay fuse for preventing premature firing of said pyrotechnic candle, a plurality of sealed pressure relief means provided in said closure in communication with the heat and pressure chamber, said pressure relief means being adapted to be unsealed by said heat and pressure generated during the burning of said time delay fuse, and means in said closure and adapted to be ruptured by the heat and pressure generated by the ignition of said pyrotechnic candle whereby a portion of the closure and the firing means supported thereby are forcibly removed from said housing to render the device effective to emit light therefrom.

7. A light emitting device adapted to float upon the surface of a body of water and comprising an elongated buoyant body having a bore extending therethrough, a pyrotechnic candle arranged within said bore, a housing secured to said buoyant body, a disc for sealing said housing hermetically to form a heat and pressure chamber therein, a firing unit supported by said disc, a time delay fuse adapted to be fired by said firing unit, said time delay fuse having means for igniting said pyrotechnic candle, a flexible tubular member enclosing said time delay fuse whereby a flashback during burning of said fuse is prevented from prematurely firing said pyrotechnic candle, a plurality of sealed relief ports in said disc in communication with said heat and pressure chamber, said relief ports being adapted to be unsealed by said heat and pressure generated by said time delay fuse during the burning thereof, and means in said disc and adapted to be ruptured by the pressure generated by the ignition of said pyrotechnic candle whereby a portion of the disc and the firing unit supported thereby are forcibly removed from said housing to render the device effective to emit light therefrom.

8. A light emitting device adapted to float upon the surface of a body of water and comprising an elongated buoyant body having a bore extending therethrough, a candle arranged within said bore, said candle comprising a plurality of cylindrical containers, a plurality of pyrotechnic charges respectively arranged within and substantially filling said containers, means independent of said bore for joining the containers

in mutual axial alinement, a plurality of separators arranged within the containers and between adjacent pyrotechnic charges whereby premature firing of the charges by friction between the charges is prevented as the containers are joined, a housing secured to said buoyant body, a closure for sealing said housing to form a heat and pressure chamber therein, firing means supported by said closure, means for firing said firing means, a time delay fuse operatively connected to said firing means, a plurality of sealed pressure relief means in said closure in communication with said heat and pressure chamber, said pressure relief means being adapted to be unsealed by the heat and pressure generated during the burning of said time delay fuse, and means in said closure and adapted to be ruptured by the pressure generated by the ignition of said candle whereby a portion of the closure and the firing means supported thereby are forcibly removed from said housing to render the device effective to emit light therefrom.

9. A light emitting device adapted to float upon the surface of a body of water and comprising an elongated buoyant body having a bore extending therethrough, a pyrotechnic candle having a first fire composition and arranged within said bore, a housing secured to said buoyant body, a closure for sealing said housing to form a heat and pressure chamber therein, firing means supported by said closure, a time delay fuse arranged within said housing and operatively connected at one end thereof to said firing means, a sack having a quantity of starter mixture therein and secured to the other end of said time delay fuse, a flexible tubular sleeve enclosing said time delay fuse whereby sparks caused by a flashback of the fuse during burning thereof are prevented from prematurely firing said pyrotechnic candle, a combustible moistureproof container enclosing said sack and adapted to rest on said first fire composition, a plurality of sealed pressure relief means in said closure, said relief means being adapted to be unsealed by said heat and pressure generated by said time delay fuse, and a weakened portion in said closure and adapted to be ruptured by the pressure generated by the ignition of said pyrotechnic candle whereby a portion of the closure and the firing means supported thereby are forcibly removed from said housing to render the device effective to emit light therefrom.

10. A light emitting device adapted to float upon the surface of a body of water and comprising an elongated buoyant body having a bore extending therethrough, a pyrotechnic candle arranged within said bore, a housing secured to said buoyant body, a disc for sealing said housing hermetically to form a heat and pressure chamber therein, a combustible moistureproof container arranged within said pyrotechnic candle and having a quantity of starter mixture therein, firing means supported by said disc, said firing means including means for igniting said starter mixture to produce a hot residue therefrom, means for firing said firing means, means including said residue for causing the ignition of the pyrotechnic candle, a plurality of sealed pressure relief means in said disc, said pressure relief means being adapted to be unsealed by the heat and pressure generated by the burning of said starter mixture igniting means, and means in said disc and adapted to be ruptured by the pressure generated by the ignition of said pyrotechnic candle for causing a portion of the disc to be forcibly removed

from said housing to render the device effective to emit light therefrom.

11. A light flare adapted to be launched from an aircraft and comprising an elongated buoyant member having a bore extending therethrough, means secured to said buoyant member for causing the flare to float upon the surface of a body of water in an upright position, a pyrotechnic candle arranged within said bore, a housing secured to the upper portion of said buoyant member in abutting relation with said bore, a disc for sealing said housing hermetically to form a heat and pressure chamber therein, firing means supported by said disc, said firing means including means for igniting said pyrotechnic candle, means for firing said firing means, a plurality of sealed pressure relief ports arranged in said disc in communication with the heat and pressure chamber, said pressure relief ports being adapted to be unsealed by said heat and pressure generated by said candle igniting means, and means included in said disc and adapted to be ruptured by the pressure generated by the ignition of said pyrotechnic candle whereby a portion of the disc and the firing means supported thereby are forcibly removed from said housing.

12. A pyrotechnic candle adapted for use in a buoyant light flare and comprising an upper container, a lower container and an intermediate container, a first pyrotechnic charge arranged within and substantially filling said upper container thereby to provide a recess within the container, a second pyrotechnic charge arranged within and filling said intermediate container, a third pyrotechnic charge arranged within and filling said lower container, means for joining said containers in mutual axial alignment with said charges in abutting relation with respect to each other, a combustible moisture-

proof capsule arranged within said recess and in abutting engagement with respect to said first pyrotechnic charge, a firing device secured to said light flare, means for actuating said firing device to a firing position, an elongated flexible time delay element having one end thereof secured to said firing device and the other end arranged within said capsule, a primer arranged within said firing device and fired thereby as the firing device is actuated to said firing position for igniting said time delay element, a pouch disposed within the capsule and secured to said other end of said time delay element, a quantity of starter mixture enclosed within said pouch for igniting said first pyrotechnic charge in time delayed relation with respect to ignition of the time delay element by said primer, and a plurality of separators disposed between and in abutting engagement with said pyrotechnic charges respectively whereby premature firing of said charges by friction between the charges is prevented as the containers are joined.
